TRANSMISSION LINE HAVING DEAD-END PORTION

Ralph W. George, Riverhead, N. Y., assignor to
Radio Corporation of America, a corporation of
Delaware

Application June 9, 1943, Serial No. 490,225

10 Claims. (Cl. 250—36)

1

This invention relates to improvements in adjustable resonant transmission line circuits such as are used at ultra high frequencies.

In employing tunable resonant transmission line circuits, such as concentric lines and lecher wires, it is customary to tune the circuit by means of an adjustable short-circuiting bar or bridge which is movable over the length of the conductors. In this type of circuit difficulties are sometimes experienced from the dead end or unused portion of the resonant line due to the effect of resonance in this unused portion which has some finite coupling with the main portion of the resonant line.

When such a resonant transmission line is employed in an ultra high frequency oscillation generator tunable over a relatively wide frequency range, there may be experienced dead spots or undue losses at certain frequencies in the tuning range. This trouble is due primarily to the aforementioned resonance effects in the unused portions of the conductors of the transmission line.

A primary object of the present invention is to eliminate or reduce, to a considerable extent, the influence of the dead end or unused portion of the tunable resonant transmission line on the desired or useful portion of the line. Putting it in other words, an object is to prevent the influence of those portions of the conductors of the line beyond the short-circuit bridge from affecting the normal operation of the system connected to the useful portion of the line.

Another object is to provide an improved ultra high frequency oscillation generator having resonance transmission line circuits and which is tunable in a continuous manner over a relatively wide frequency range so that satisfactory operation is obtainable throughout the entire frequency range.

A further object is to provide a tunable signal generator having adjustable resonant transmission line circuits and which is capable of satisfactory operation over all points of a frequency range on the order of 550 to 1400 megacycles.

A feature of the invention lies in the use of a parallel conductor transmission line circuit having an adjustable short-circuiting slider. One end of the circuit is connected to an energizing unit and the other end is connected to a D. C. circuit. A damping resistor is placed at a suitable point on the unused portion of the transmission line circuit for the purpose of damping undesirable resonance effects.

Another feature lies in the use of a transmission line circuit having a pair of parallel

2

conductors, one conductor of which is in the form of an angle-shaped member and the other conductor of which is in the form of a rod suitably placed within the sides of the angle formed by said member. One side of the angle member is provided with a slot extending substantially over its length and which slot guides a slider for connecting the rod to the angle member. Suitably placed short-circuiting straps are connected over the length of the angle member between the two sides thereof for preventing resonance from building up in the slotted member at frequencies near the operating frequency of the system.

Further objects and features will appear hereinafter.

A more detailed description of the invention follows in conjunction with the drawing, wherein Figure 1 illustrates one embodiment of an oscillator generator constructed in accordance with the principles of the invention; Figure 2 illustrates a detail of the short-circuiting slider along the line 2—2 of Figure 1; and Figure 3 is a plan view of the short-circuiting slider as seen looking down on the transmission line circuit of Figure 1.

Referring to Figure 1, in more detail, there is shown an oscillator generator comprising a three electrode vacuum tube 10 having a grid 11, an anode 12 and a filament 13. The circuit of the oscillator generator, except for the improvements to be hereinafter noted, is similar to the oscillator generator described in and illustrated in Figure 4 of my copending application, Serial #408,570, filed August 28, 1941, now U. S. Patent No. 2,399,481, granted April 30, 1946. The grid, anode and filament electrodes have individually associated therewith adjustable resonant transmission line circuits, as will hereinafter be described, as a result of which high frequency oscillations are produced over a relatively wide frequency range; for example, over a range from 550 to 1400 megacycles.

The grid and anode tuned circuits each comprise an adjustable transmission line circuit having an angle-shaped member 14 and a rod 15 placed substantially symmetrically within the sides of the angle formed by the member 14. The conductors 14 and 15 of each tuned circuit are of high electrical conductivity and may be copper plated with silver or gold. The vertical side of the angle member 14 is provided with a slot 16 which extends substantially over its entire length, as shown, and which serves to guide a movable short-circuiting slider or bridge. Both the grid and the anode transmission line circuits

3

have their angle members 14 mounted on a metallic base plate 17 which is grounded. A mica spacer 18 is placed between each angle member 14 and the base plate 17 for isolating the angle member 14 from ground from a D. C. standpoint. The angle member 14 is by-passed to ground for radio frequencies.

Each of the transmission line circuits 14, 15 may be compared to a concentric transmission line wherein part of the outer conductor 14 has been removed and wherein rod 15 constitutes the inner conductor. The inner conductor 15 is mechanically supported from the outer conductor at the end removed from the vacuum tube 10 by means of an insulating block 19. A short-circuiting slider is driven by means of an insulation block 20 threadedly engaging a lead screw 21. This slider serves to bridge or connect the conductors 14 and 15 as it moves along the length of the transmission line under control of the lead screw in a manner described in more detail hereinafter in connection with Figures 2 and 3.

To prevent resonance from building up in the side portions of the slot 16 at frequencies near the operating frequency of the oscillation generator, there are provided for each transmission line a pair of metallic short-circuiting straps 22, 22 which connect the side edges of the angle member. The straps 22, 22 effectively short-circuit the sides of the slot and thus divide the slot into circuits which have resonance frequencies considerably higher than the operating frequency of the system. It will be seen that these straps are so arranged that they do not interfere with the mechanical operation of the sliders along the lengths of the slots.

A damping resistor 23 is provided at each end of the grid and anode line sections which is removed from the vacuum tube to damp the resonance in the dead end or unused portion of the line 14, 15. This unused portion is that part of the transmission line which appears between the short-circuiting slider and the end of the line adjacent insulating block 19. The resistor 23 is bridged between the conductors 14, 15, as shown, and has a rather low resistance value of the order of the characteristic impedance of the line. As an example, the resistor may be between 25 to 75 ohms. If desired, the damping resistor 23, instead of being in shunt to the conductors of the transmission line 14, 15, as shown, may be placed in series with the inner conductor 15 at a point where maximum current occurs for undesired resonance, considering, of course, that portion of the line between the slider and the D. C. circuit. The grid is supplied with a suitable bias by way of lead 24 and grid leak 25. The anode is supplied with a polarizing potential by way of lead 26 and low pass filter 47, one end of which is connected to the positive terminal +B of a source of anode potential. The lengths of the leads 24 and 26 will affect the effectiveness of the damping resistor and will indicate whether shunt or series damping should be used.

In order to more effectively tie together the outer conductors 14 of the anode and grid transmission line circuits at the ends near the tube electrodes, there has been provided an added capacity between these two outer conductors in the form of a strip of metal 27, which is directly connected to one of the conductors 14 and capacitively coupled to the other conductor 14 by means of a mica spacer 28. If desired, this metal strip 27 can be replaced by a condenser of conventional construction. This auxiliary capacity

provides improved operation at medium and high frequencies over the tuning range.

The filament 13 of vacuum tube 10 is shown connected to a filament supply circuit through a tunable coaxial transmission line system 48. A suitable slider 29 serves to tune the filament by connecting any desired portion of the outer conductor of the coaxial line 48 to a suitable ground plate 30. In practice, ground plate 30 can form part and parcel of the base plate 17. The filament tuning system, if desired, may employ an adjustable transmission line circuit identical with conductors 14 and 15 and with a short-circuiting bar or slider arrangement similar to that shown for the transmission line circuit 14, 15.

Reverting to the consideration of the short-circuiting slider for the transmission line circuit 14, 15, it will be seen that both lead screws 21 are uncontrolled by means of a dial 31. The mechanical connections between the lead screws are shown in conventional manner by the dash lines 32 and may comprise any suitable mechanical arrangement.

Figure 2 illustrates a side view of the slider construction for the transmission line circuit 14, 15 along the line 2-2 of Figure 1. The slider, in effect, comprises upper and lower contact members 33 in engagement with the rod 15. Members 33 preferably have a silver inlay for contact purposes secured to a brass T-shaped slider 34 whose central arm passes through the slot 16 for cooperation with an insulation block 20 through which the lead screw passes. The slider 34 is held in contact with the sides of the slot by means of a beryllium copper spring 35 which accommodates steel balls 36 on both sides of the slot. On the inner side of the angle member 14 there are provided silver inlays 37 for maintaining good electrical contact between the conductor 14 and the brass member 34. In effect, there are two contact members 33 above conductor 15 and two similar contact members below conductor 15 in corresponding positions. This is seen more clearly from an inspection of Figure 3. The slider is so designed that the elements, when assembled, maintain good electrical contact points in spite of irregularities in alignment of the parts.

The grid and anode electrodes of the tube 10 are provided at the side of the envelope removed from the transmission line circuits 14, 15 with fixed inductor elements comprising concentric line sections 38, 38. The inner conductors of the concentric line inductors are capacitively coupled to the grid and anode electrodes, respectively, through blocking condensers 39. These fixed inductors serve to complete the oscillation generator circuit. A suitable output circuit, here shown as a loop 40, enters the interior of one of the fixed concentric inductor lines 38 to derive output energy from the generator.

In one embodiment of the invention tried out in practice in connection with a signal generator, vacuum tube 10 was a W. E. 368-A tube. The signal generator functioned over a tuning range from approximately 550 to 1400 megacycles, although the vacuum tube employed in this embodiment was of the type wherein the grid and anode electrodes were each provided with a pair of terminals extending from opposite sides of the envelope. It should be understood that this particular embodiment was employed primarily for obtaining the high frequencies and the wide frequency range desired.

Obviously, the features of the invention can be

employed in connection with other oscillation generator systems wherein similar difficulties due to undesired resonance effects of the unused portions of tuned transmission line circuits are encountered.

What is claimed is:

1. A high frequency system comprising a pair of parallel conductors forming a tuned transmission line, a short-circuiting bar intermediate the ends of said line for tuning a circuit connected to one end thereof, and a damping resistor of the order of the characteristic impedance of the line in circuit with the other end of said line for damping oscillations therein.

2. A high frequency system comprising a pair of parallel conductors forming a tuned transmission line, a short-circuiting bar intermediate the ends of said line for tuning a circuit connected to one end thereof to a desired frequency, one of said conductors having a slot therein along the length thereof for guiding said short-circuiting bar, and fixed means for bridging said slot at a plurality of points along its length.

3. A high frequency system comprising a pair of parallel conductors forming a tuned transmission line, a short-circuiting bar intermediate the ends of said line for tuning a circuit connected to one end thereof to a desired frequency, one of said conductors having a slot therein along the length thereof for guiding said short-circuiting bar, a damping resistor in circuit with the other end of said line, and fixed means for bridging said slot at a plurality of points along its length.

4. A high frequency system comprising a pair of parallel conductors forming a tuned transmission line, a short-circuiting bar intermediate the ends of said line for tuning a circuit connected to one end thereof to a desired frequency, one of said conductors having a slot therein along the length thereof for guiding said short-circuiting bar, and a plurality of metallic straps bridging said slot at a plurality of points along its length, to thereby cause the resonant frequency of any portion of the slot member to exceed the operating frequency of the system.

5. A system in accordance with claim 4, characteristic in this, that the conductor having the slot is in the form of an angle-shaped member, while the other conductor is a rod located within the angle formed by the sides of said member.

6. A high frequency system comprising a vacuum tube having a pair of cold electrodes, individual tunable transmission lines for said cold electrodes, each of said lines having substantially along its entire length one conductor connected through a path of low impedance at radio frequency to ground, and a capacity providing still lower impedance between those ends of said last conductors which are nearest said cold electrodes.

7. A high frequency system comprising a vacuum tube having anode and grid electrodes, separate tunable transmission lines connected at one end to each of said electrodes, said lines being parallel to each other and extending on the same

side of said tube, a common ground plate, a capacity connection from one conductor of each of said lines to said common ground plate, and an auxiliary capacity connection between the ends of said one conductors at the location nearest said electrodes.

5 8. A high frequency system comprising a pair of parallel conductors forming a tuned transmission line, a short-circuiting bar intermediate the ends of said line for tuning a circuit connected to one end thereof to a desired frequency, one of said conductors having a slot therein along the length thereof for guiding said short-circuiting bar, a damping resistor in circuit with the other end of said line, and fixed means for bridging said slot at a plurality of points along its length, said circuit comprising a vacuum tube having an electrode connected to said line.

10 9. A high frequency system comprising a vacuum tube having anode and grid electrodes, separate tunable transmission lines connected at one end to each of said electrodes, said lines being parallel to each other and extending on the same side of said tube, a common ground plate, a capacity connection from one conductor of each of said lines to said common ground plate, an auxiliary capacity connection between the ends of said one conductors at the location nearest said electrodes, and damping resistors in shunt to said lines at their ends remote from said vacuum tube.

15 10. An ultra high frequency system comprising a vacuum tube having a pair of cold electrodes, individual tunable transmission lines connected at one end to said cold electrodes, a movable short-circuiting slider intermediate the ends of each line for tuning the same, said lines being parallel and located on the same side of said tube, each of said lines having one conductor connected through a path of low impedance at 20 radio frequencies to ground, a capacity providing still lower impedance between said one conductors at those ends nearest said vacuum tube, a damping resistor for each of said lines at a location near the end remote from said vacuum tube, said resistor having a value of the order of the characteristic impedance of the line to which it is connected, said one conductor of each line having a slot for guiding the slider associated with the same line, and fixed metallic straps bridging the 25 slots of said lines at a plurality of points along their lengths.
